COLLAPSIBLE TABLE

Robert H. Gwynn, Glendale, Calif.

Application May 8, 1933, Serial No. 669,813

10 Claims. (Cl. 45—11)

The general object of the invention is to provide a strong and rigid table of the character stated, without legs at the corners thereof to form obstructions, but with detachable and foldable legs, which may be unfolded across each other at an angle and supported one upon the other, for supporting the top of the table, which may be detachably secured to the upper ends of the legs, and which legs may be detached from the table top and folded out flat, side by side, and detachably secured to the under side of the top, when the table is not desired for use.

Another object is to provide a table of the character stated which is simple in construction, inexpensive and easy to set up in position for use or to take down and fold up when not in use.

Other objects and advantages will appear hereinafter.

The invention is illustrated in the annexed drawings which form a part of this specification and in which,

Fig. 1 is a plan view of the legs of the table shown detached from the table top and folded out flat.

Fig. 2 is a view like Fig. 1 except that one of the legs is shown unfolded.

Fig. 3 is a view like Fig. 1 except that two of the legs are shown unfolded.

Fig. 4 is an elevation of the legs shown all unfolded into position for supporting the table top.

Fig. 5 is a view like Fig. 4 with the top of the table shown detachably secured to the upper ends of the legs of the table.

Fig. 6 is an elevation of the assembled table but shown at an angle of forty-five degrees to the position of the table as shown in Fig. 5.

Fig. 7 is a bottom plan view of the assembled table.

Fig. 8 is a bottom plan view of the table in collapsed position, showing the legs folded out flat side by side and detachably secured to the under side of the top.

Fig. 9 is a fragmentary side view of one of the table legs and pivot pins, showing also the adjacent leg in dotted lines pivoted to the leg shown in full lines.

Fig. 10 is a view like Fig. 9 but taken at right angles thereto.

Fig. 11 is a fragmentary vertical section of the table top and one leg detachably secured thereto, taken on line 11—11 of Fig. 7.

Fig. 12 is a bottom plan view of Fig. 11 with the leg removed, showing the slotted plate to which the engaging plate on the leg is detachably se-

cured for detachably securing the table top to the upper ends of the legs.

Fig. 13 is a view of the legs of the table shown folded out flat and pivoted one to another by hinges instead of pivot pins, as illustrated in Figs. 9 and 10.

Referring in detail to the drawings my table comprises generally four legs designated respectively 1, 2, 3 and 4, and a top designated 5.

The leg 1 is pivoted to the leg 2 by a pivot pin 6. The leg 2 is pivoted to the leg 3 by a pivot pin 7. The leg 3 is pivoted to the leg 4 by a pivot pin 8. The pivot pins 6, 7 and 8 extend at an angle of substantially forty-five degrees to the legs, so that they may extend vertically to allow the legs to be unfolded into supporting position, in which position the legs extend at an angle of substantially forty-five degrees to the vertical (Figs. 4, 5 and 6). The legs 1, 2, 3 and 4 respectively are provided with notches 9, 10, 11 and 12 in their upper side edges to receive the lower edges of the legs 4, 1, 2 and 3 respectively, whereby the legs, when unfolded into supporting position, are supported one upon the other and held rigidly together to provide a strong and rigid support for the table top 5, when secured upon the upper ends of the legs, as will be more fully described hereinafter.

Engaging plates 13 are secured to the upper ends of the legs for engaging slotted plates 14 secured to the under side of the table top 5, diagonally of the top, said engaging plates being formed with lugs 15 for extending through slots 16 in said slotted plates and engaging the inner sides of said slotted plates over the end edges 17 of said slots, and there being spring locking plates 18 secured to the inner sides of said slotted plates for engaging said engaging plates and locking said lugs in engagement with said slot edges for detachably securing said table top in position on the upper ends of said legs. Buttons 19 are formed on said locking plates which extend through openings 20 in the slotted plates 14, which buttons may be depressed for disengaging said locking plates from said engaging plates, so that the top 5 may be detached from the upper ends of said legs.

In the upper edge of the leg 1 is provided a socket 21 to receive a pin 22 secured in a block 23 which is secured to the under side of the top 5 of the table, and in the lower edge of the leg 4 is provided a socket 24 to receive a spring-pressed pin 25 mounted in a block 26 secured to the under side of the table.

The operation, advantages and uses of my invention are as follows:

The table is set up by unfolding the legs 1, 2, 3 and 4 and pivoting them into supporting position, in which position the legs extend at an angle of substantially forty-five degrees to the vertical (Figs. 4, 5 and 6). The legs 1, 2, 3 and 4 respectively are provided with notches 9, 10, 11 and 12 in their upper side edges to receive the lower edges of the legs 4, 1, 2 and 3 respectively, whereby the legs, when unfolded into supporting position, are supported one upon the other and held rigidly together to provide a strong and rigid support for the table top 5, when secured upon the upper ends of the legs, as will be more fully described hereinafter.

Engaging plates 13 are secured to the upper ends of the legs for engaging slotted plates 14 secured to the under side of the table top 5, diagonally of the top, said engaging plates being formed with lugs 15 for extending through slots 16 in said slotted plates and engaging the inner sides of said slotted plates over the end edges 17 of said slots, and there being spring locking plates 18 secured to the inner sides of said slotted plates for engaging said engaging plates and locking said lugs in engagement with said slot edges for detachably securing said table top in position on the upper ends of said legs. Buttons 19 are formed on said locking plates which extend through openings 20 in the slotted plates 14, which buttons may be depressed for disengaging said locking plates from said engaging plates, so that the top 5 may be detached from the upper ends of said legs.

In the upper edge of the leg 1 is provided a socket 21 to receive a pin 22 secured in a block 23 which is secured to the under side of the top 5 of the table, and in the lower edge of the leg 4 is provided a socket 24 to receive a spring-pressed pin 25 mounted in a block 26 secured to the under side of the table.

The table is collapsed by pivoting the legs 1, 2, 3 and 4 into a flat position and folding them side by side, and then pivoting them into a position where the legs 1, 2, 3 and 4 are supported one upon the other, and then detaching the top 5 from the legs 1, 2, 3 and 4 by depressing the buttons 19 on the locking plates 18 and then detaching the top 5 from the legs 1, 2, 3 and 4 by detaching the engaging plates 13 from the slotted plates 14.

The table is collapsed by pivoting the legs 1, 2, 3 and 4 into a flat position and folding them side by side, and then pivoting them into a position where the legs 1, 2, 3 and 4 are supported one upon the other, and then detaching the top 5 from the legs 1, 2, 3 and 4 by depressing the buttons 19 on the locking plates 18 and then detaching the top 5 from the legs 1, 2, 3 and 4 by detaching the engaging plates 13 from the slotted plates 14.

The legs 1, 2, 3 and 4 of my table fold up flat, on the pivots 6, 7 and 8, with the lower side edges of the legs 1, 2 and 3 resting respectively against the upper side edges of the legs 2, 3 and 4, as

5 shown in Figs. 1, 8 and 13 of the drawings, and the legs unfold on said pivots progressively, as illustrated in Figs. 1, 2, 3 and 4, into supporting position (Fig. 4) with the legs extending at angles of substantially forty-five degrees and the

10 lower edges of the legs 4, 1, 2 and 3 resting in the notches 9, 10, 11 and 12 respectively in the upper side edges of the legs 1, 2, 3 and 4, whereby the legs are braced one against the other to form a strong and rigid support for the top 5 of the table.

15 In the position of the legs shown in Fig. 4, the top 5 of the table is placed upon the upper ends of the legs and detachably secured thereto upon inserting the lugs 13 on the upper ends of the legs into the slotted plates 14 in the bottom of 20 the top, as shown in Figs. 5 and 11. With the top of the table detachably secured to the upper ends of the legs, as shown in Figs. 5 and 6 the table is set up in position for use.

25 When the table is not in use the top 5 may be detached from the upper ends of the legs 1, 2, 3 and 4, by withdrawing the lugs 13 from engagement with the slotted plates 14, and the legs may then be folded, as shown in Fig. 1, and placed against the under side of the top, between the blocks 23 and 25 and secured in such position upon inserting the pin 16 into the socket 15 in the leg 1 and inserting the pin 19 into the socket 18 in the leg 4, thus folding and packing up the table for storage or transportation.

30 35 To remove the folded legs from the under side of the table top it is only necessary to withdraw the spring-pressed pin 25 from the socket 24 in the leg 4 and lift the legs, the leg 4 foremost, from between the blocks 23 and 24, the pin 22 withdrawing from the socket 21 to permit such removal of the legs from the top.

40 The position of the slotted plates 14, on the table top, to which the engaging plates 13, on the legs, are detachably secured, positions the legs diagonally of the top, whereby it is possible to spread the lower ends of the legs further apart without extending outwardly beyond the edges of the table top, thus giving the legs a wider and more substantial supporting base than otherwise if the legs extended parallel to edges of the table.

45 The construction and arrangement of the legs of my table eliminates legs at the corners of the table, which form obstructions that are often in the way of persons using the table or walking near the same.

50 The legs of my table, instead of being pivoted together by the pivot pins 6, 7 and 8, may be hinged one to another by hinges 26, 27 and 28, as illustrated in Fig. 13.

55 60 I claim as my invention:

1. A table comprising a plurality of legs pivoted one to another on pivots extending diagonally across the adjoining side edges of adjoining legs to unfold into supporting position at an angle, with each leg resting upon and supported by another leg, and to fold up into a flat position with adjacent legs resting with their side edges one against another, a table top, means for detachably securing said top upon the upper ends of said legs when unfolded into supporting position.

65 70 75 2. A table comprising a plurality of legs pivoted one to another on pivots extending diagonally across the adjoining side edges of adjoining legs to unfold into supporting position

80 at an angle, with each leg resting upon and supported by another leg, and to fold up into a flat position with the side edges of adjacent legs resting one against another, one edge of each leg being formed with a notch to receive the opposite edge of an adjacent leg, when said legs are unfolded into supporting position, a table top, means for detachably securing said top upon the upper ends of said legs, when unfolded into supporting position.

85 3. A table comprising a plurality of legs pivoted one to another on pivots extending diagonally across the adjoining side edges of adjoining legs to unfold into supporting position at an angle, with each leg resting upon and supported by another leg, and to fold up into a flat position with the side edges of adjacent legs resting one against another, the upper edge of each leg being formed with a notch to receive the lower edge of an adjacent leg, when said legs are unfolded into supporting position, a table top, means for detachably securing said top upon the upper ends of said legs, when unfolded into supporting position.

90 4. A table comprising a plurality of legs pivoted one to another on pivots extending diagonally across the adjoining side edges of adjoining legs to unfold into supporting position at an angle with their pivots extending vertically and with each leg resting upon and supported by another leg, and to fold up into a flat position with the side edges of adjacent legs one against another, a table top, means for detachably securing said top upon the upper ends of said legs when unfolded into supporting position.

95 100 105 5. A table comprising a plurality of legs pivoted one to another to unfold into supporting position at an angle with each leg resting upon and supported by another leg, and to fold up flat with the side edges of adjacent legs resting one against another, a table top, means for detachably securing said top upon the upper ends of said legs when unfolded into supporting position, blocks secured to the under side of the top between which said legs, when their upper ends are detached from said top and folded flat, are placed, means for detachably securing said folded legs between said blocks.

110 115 120 6. A table comprising a plurality of foldable legs pivoted one to another on pivots extending diagonally across adjoining edges of adjoining legs to unfold into supporting position at an angle, with each leg resting upon and supported by another leg and to fold up into a flat position, a table top, and means for detachably securing said top upon the upper ends of said legs when unfolded, with the legs extending diagonally of the top.

125 130 135 7. A table comprising a plurality of legs pivoted one to another to unfold into supporting position, engaging plates secured to the upper ends of said legs respectively, a top for the table, slotted plates secured to the under side of the top to be engaged by said engaging plates, when said legs are unfolded into supporting position, for detachably securing said top to the upper ends of the unfolded legs, and locking plates for detachably locking said engaging plates in engagement with said slotted plates.

140 145 8. A table top as characterized by claim 1 including means for detachably securing said legs, when folded up flat, to the under side of the table top.

9. A folding leg construction comprising a plu- 150

rality of legs pivoted each to the next on pivot axes diagonal to the adjoining edges of the legs, in such manner that said legs may be swung on said axes into a substantially flat position adjacent and parallel to one another, or moved from 5 said position into an operative position with each leg extending at an angle to and resting upon the adjacent leg.

10. A folding leg construction comprising a

plurality of legs, hinges secured to one side of said legs with each hinge pivot extending at an angle across the adjoining edges of two adjoining legs, to enable said legs to fold adjacent and parallel to one another into flat position and to 80 unfold into operative position with each leg extending at an angle to and resting upon an adjacent leg.
